Carl Müller

United States Patent Office.

CARL MÜLLER, OF NEW YORK N. Y.

Design No. 2,944, dated March 3, 1868.

DESIGN FOR A FIGURE AND BASE.

The Schedule referred to in these Letters Patent and making part of the same.

TO ALL WHOM IT MAY CONCERN:

Be it known that I, CARL MÜLLER, of the city, county, and State of New York, have invented a new and ornamental Design for Figure and Base; and I do hereby declare that the following is a full, clear, and exact description thereof, which will enable those skilled in the art to make and use the same, reference being had to the accompanying drawing, forming a part of this specification, which drawing represents a front-view of the design.

This invention relates to a design for a figure and base, said figure being a stone-cutter or sculptor, S, inclining a little to the left, and resting mainly on his right foot, holding in his right hand a hammer, and in his left a chisel, with which he is in the act of carving ornaments on a capital, C, the capital lying on a rough stone, D, the whole standing on the base, B, which is of a round shape. The rough stone D is embellished by a compass, E, and a mallet, E', leaning against it.

What I claim as new, and desire to secure by Letters Patent, is—

The design for a figure and base, as herein shown and described.

The above specification signed by me, this 22d day of January, 1868.

CARL MÜLLEE,

Witnesses:

HENRY RASSIGA,

CHARLES KITSCHELT.
